UNITED STATES PATENT OFFICE.

ERNEST O. R. KRESSE, OF BROOKLYN, NEW YORK.

SHOE-HEEL.

1,392,769.

Specification of Letters Patent.

Patented Oct. 4, 1921.

Application filed November 15, 1916. Serial No. 131,428.

To all whom it may concern:

Be it known that I, ERNEST O. R. KRESSE, a citizen of the United States, residing at Brooklyn, in the county of Kings and State 5 of New York, have invented certain new and useful Improvements in Shoe-Heels; and I do hereby declare the following to be a full, clear, and exact description of the invention, such as will enable others skilled in the art 10 to which it appertains to make and use the same.

This invention relates to improvements in heels of that type consisting of a body of wood having a cloth or celluloid jacket 15 thereon, and top lift made of leather, metal preferably of aluminum or other material secured to the lower face of the wooden body, and the primary object of the invention is to admit of the wooden body being 20 effectively reinforced against lateral strain so that the body will not become broken.

Another object of the invention is the provision of a novel type of fastening means for securing the heel on the shoe.

25 Another object of the invention is the provision of a novel fastening means for detachably securing the top lift to the wooden portion of the heel so as to admit of the top lift being easily removed when 30 worn, so that a new top lift may be substituted therefor.

A still further object of the invention is the provision of a novel type of protector plate adapted to be interposed between the 35 wooden body and the top lift, so as to prevent the wearing of the lower portion of the jacket, should the top lift become accidentally detached from operative position.

Other objects will appear and be better 40 understood from that embodiment of my invention of which the following is a specification, reference being had to the accompanying drawing forming a part thereof, in which:

45 The figure is a detail sectional view of the heel portion of a shoe with the heel attached thereto, and showing the latter in section so as to illustrate the preferred form of fastening and reinforcing means for the 50 heel.

Referring to the drawing in detail, the 55 numeral 1 designates the heel portion of a shoe, and 2 a shoe heel which consists of a wooden body designed to be incased within a cloth, leather, or celluloid jacket, and 3 indicates the top lift which is detachably as-

sociated with the lower portion of the wooden body of the heel. The wooden body portion of the heel is provided with a longitudinally extending bore, which receives 60 a cylindrical shaped element 4, which serves as a reinforcement for the heel so as to prevent the latter from becoming broken under lateral strain. The cylindrical shaped element 4 is hollow, and has its upper end 65 flattened, as shown at 5, and countersunk in the upper side of the wooden portion of the heel, so as to prevent the cylindrical element 4 from having downward longitudinal movement within the bore when in 70 the position shown. The inner surface of the cylindrical element 4 is threaded at the opposite ends of the element, and a screw 6 extends through the sole of the shoe and is threadedly received by the upper end of 75 the cylindrical element 4. When the heel 2 is mounted in position upon the sole of the shoe, a plurality of small nails, not shown, are driven through the upper portion of the heel and through the sole of the 80 shoe, after which the screw 6 is passed through the sole and into the cylindrical element 4, and assist in holding the heel on the shoe. Interposed between the wooden portion of the heel and the top lift 3 is a 85 protector plate 7. This plate 7 conforms to the configuration of the top lift 3 and is preferably formed of steel and is provided with a series of cutout portions 8, so as to lessen the weight of the plates. The plate 90 7 is centrally provided with a circular head 9 which is centrally provided with an opening that registers with an opening in the top lift 3 and with the interior of the hollow cylindrical shaped element 4. A fastening screw 10 has its shank extended through the aligned openings in the top lift 3 and the circular head 9 and is threadedly received by the lower end of the hollow cylindrical element 4, so as to secure the 100 top lift 3 and plate 7 in operative position, the head of the screw being countersunk in the lower face of the top lift 3.

It is evident that various changes might be resorted to in the construction, form and arrangement of the several parts without departing from the spirit and scope of the invention, as claimed.

Having thus described my invention what I claim as new is:—

A shoe heel including a body having a vertical bore extending therethrough and a

wear plate engaging one end of the body and engaged by a lift, a reinforcing tube fitting snugly in the bore and having its upper end flared and countersunk in said body to prevent displacement from the bore, said member being internally screw threaded adjacent said end, a fastening screw constructed and arranged to extend through the sole of a shoe, said flared end engaging said

screw threads, and means to support the 10 wear plate from the tube.

In testimony whereof I affix my signature in presence of two witnesses.

ERNEST O. R. KRESSE.
